UNITED STATES PATENT OFFICE.

EDWARD P. MCOLVIN, OF WOLF SUMMIT, WEST VIRGINIA.

LAMP.

Application filed April 22, 1925. Serial No. 25,082.

It is not uncommon for miners to remove the gas excluding tops of their lamps when in a mine in order that they may light their pipe from the flame of the lamp, and for other unnecessary purposes. This has caused explosions with disastrous results and therefore it may be considered the object of this invention to produce a lamp for miners use in which the bowl cannot be separated from the top of the lamp without extinguishing the flame, and also of a construction that if the wick is lighted when the bowl is removed from the top part of the lamp, that it cannot be replaced without the light becoming extinguished, therefore, nothing could be gained by removing the bowl for the purpose of relighting it.

The invention resides in the novel construction, combination and arrangement of parts, a satisfactory embodiment of which being illustrated by the accompanying drawings, set forth in the following description or pointed out with particularity in the appended claim:

23 Figure 1 is a side elevation of a miner's lamp embodying my improvement, parts being broken away and parts in section.

Figure 2 is a section on line 2—2 of Figure 1.

30 Figure 3 is a sectional view through the upper threaded member of the improvement and the ring member which forms a shoulder therefor.

35 The upper gas excluding portion of the lamp is of any ordinary or well known construction and is designated by the numeral 1 of the drawings. The posts that surround the globe 2 of the said upper portion of the lamp are fixed to a barrel 3. The barrel has the lower portion of its bore larger than the upper portion thereof, but both of the said portions of the bore are formed with threads 4 and 5 respectively. Screwed in the upper threads there is an annulus 6 against which the lower end of the globe 2 rests. The annulus is integrally formed with a continuous flange 7 and arranged at approximately the center thereof and let in and secured to the bore of the said annulus 6, below the flange 7 there is a ring member 8. The passage between the ring and flange has received therein an angularly out-turned flange 9 on the upper or outer end of a sleeve 10. In this manner it will be seen that the sleeve is revolvably associated with the annulus 6.

The sleeve 10 is centrally formed with an

inwardly directed flange or partition 11 on whose inner periphery there is formed what I will term an extinguishing tube 12. The tube 12 is of the usual construction, that is, the same comprises two connected semi-circular members and the said tube receives therethrough the wick tube 13, which, of course, is of a similar construction to the extinguisher tube. The wick tube 13 passes through and is secured to the top member 14 of fount 15 of the lamp. By this it will be seen that when the fount 15 is unscrewed from the barrel 3 that the wick tube would be drawn down through extinguisher tube 12 which remains intact in the members screwed in the upper part of the barrel 3, and as the wick tube was drawn down through the extinguisher tube 12 the light would be extinguished. The tube 13 is arranged on the central partition 16 in the said member 14 and the member 14 has its outer end provided with exterior threads.

It can be seen that by the use of the different hand threads that it will be impossible to remove the parts holding the extinguisher tube at the same time the bowl or fount is removed, as they must be turned in different directions to remove them. Arrangements are to be made for air inlets as shown at "A" the same as are used in lamps now on the market. These inlets are to be protected by a gauze ring 19 the same as are now in use. Extension "B" on barrel 3 is for a shield for inlet holes "A".

The flange or partition 11 in the sleeve 10 is provided with a rectangular hole 20 for the insertion of an internal igniter of the ordinary type. By this arrangement it is to be noted that the lamp cannot be lighted until the parts constituting the same are assembled. It is obvious that should the bowl be removed from the remainder of the lamp the wick tube passing through the extinguisher tube 12 will smother the light from the wick. Also should the wick be lighted when the bowl is removed the flame therefrom would be smothered when the wick tube is again passed through the extinguisher. The construction is such that the parts constituting the same cannot be readily disassociated and assembled except by those acquainted with the construction and it is believed that the foregoing description when taken in connection with the drawings will fully set forth the advantages of my improvement to those skilled in the art to

which such inventions relate. The device, of course, is not to be restricted to the illustrated embodiment herein disclosed, as such changes may be made therefrom as fairly fall within the scope of what I claim.

Having described the invention, I claim:—

In a safety miner's lamp, a fount, an annular top member therefor exteriorly threaded adjacent its upper end, a centrally arranged partition in said top member, a wick tube rising from said partition, a barrel threaded onto said top member, an annulus threaded into the upper end of said barrel, and including an inwardly directed

continuous flange constituting a support for the globe of the lamp, a sleeve arranged between said annulus and said top member and having an upwardly directed flange engaging the flange of said annulus, a centrally located partition within said sleeve, an extinguishing tube supported by said partition and receiving said wick tube, and a gauge ring surrounding said sleeve and reposing upon the partition of said top member, said top member having air inlet openings.

In testimony whereof I affix my signature.

EDWARD P. McOLVIN.
